UNITED STATES PATENT OFFICE.

HARVEY C. BRICE AND WILLIAM C. SMITH, OF LA CROSSE, WISCONSIN.

RAILWAY-FROG.

SPECIFICATION forming part of Letters Patent No. 394,754, dated December 18, 1888.

Application filed September 19, 1888. Serial No. 285,769. (No model.)

To all whom it may concern:

Be it known that we, HARVEY C. BRICE and WILLIAM C. SMITH, citizens of the United States, residing at La Crosse, in the county of 5 La Crosse and State of Wisconsin, have invented certain new and useful Improvements in Railway-Frogs; and we do hereby declare the following to be a full, clear, and exact description of the invention, such as will enable others skilled in the art to which it app-10 pertains to make and use the same.

Our invention relates to improvements in railway-frogs; and the object of our invention is to provide a means of making a continuous 15 rail with the frog-point by hinging the same in a novel manner, and in locating and operating the frog-point upon a novelly-constructed bed-plate. We attain this object by a certain combination and arrangement of 20 parts, which will be fully described in this specification, and illustrated in the accompanying drawings, in which—

Figure 1 is a perspective view of the frog-point. Fig. 2 is a similar view of the bed-plate, 25 Fig. 3 is an end view of the portion which constitutes a part of the hinge of the frog-point. Fig. 4 is a view of one of the sheaves through which the operating-lever rod passes. Fig. 5 is a plan view of our invention com-30 pleted and ready for use. Fig. 6 is a longitudinal sectional view on the line $x x$, Fig. 5. Fig. 7 is a view of the operating lever or arm attached to the frog-point.

A designates the frog-point, which is con-35 structed in the ordinary way, with the exception of the angular shoulders a and the semi-circular reduced portions a' , which form a tongue that is adapted to fit into the cavity c in one end of the piece C.

40 B represents the bed-plate, which is constructed with the angular shoulders b and b' , the projections b^2 , and the raised portions b^3 . Said plate is thicker at the end where the frog-point is hinged, for the purpose of being 45 embedded in the cross-tie at this point and securely held in position. The projections b' and the raised portions b^3 are to keep the frog-point A in position and prevent it from twisting or springing out of shape, owing to the

lateral strains caused by the cars passing 50 over it.

The plate B is spiked to the cross-ties, so that the angular shoulders b and b' will fit closely against the ends of the rails D D and E E. This holds said bed-plate securely, preventing it from slipping backward or forward. It will be observed that when the plate B is thus located the end b^4 fits closely in between the ends of the rails E E. 55

The piece C is constructed, as shown in Fig. 60 3, with a view of being adapted to fit closely between the ends of the rails D D, where the piece is bolted by means of the bolts d . The cavity c is formed to receive the tongue formed upon the end of the frog-point by 65 means of reducing the same upon both sides. It will readily be seen that the ends of the frog-point A and the piece C, being thus constructed, are adapted to each other, and when placed together they form a hinge, F, by means 70 of which the frog-point A is operated. Said hinge is pivoted with the bolt f , which has its head countersunk in the end of piece C. The hinge F being thus arranged and constructed, it cannot possibly get out of order or 75 place. The piece C may be cast solid with the rails, so as to constitute a part thereof; but frequently we find it convenient to make it independently of them, as before described.

G is one of the sheaves, which are secured to 80 the cross-ties in which the rod H works. The rod I is secured to the frog-point A by means of bolts. Said rod connects with the bell-crank lever J, which is pivoted to the plate K on the cross-tie and bolted to the horizontal 85 rod H. The rod H is attached to another bell-crank lever, L, at the switch, which is pivoted on another plate.

M represents the arm of the switch-stand, which transmits motion to the bell-crank lever L. This imparts motion to the horizontal rod H, thence to the right-angled lever J, which operates the rod I, that is attached to the frog-point A, by means of which said frog-point can be easily thrown to either rail E E. 90

We do not wish to limit ourselves to the precise construction of hinge described and shown, as we desire to include any construc-95

tion involving our improved plate B and part C.

It being apparent that our invention is practical and effectual in operation, it is useless 5 to further enlarge upon its merits.

What we claim is—

1. In a frog-point for making a continuous rail, the combination of the bed-plate B, the movable frog-point A, the piece C, the rails D 10 D, whereby the hinge F is formed, and suitable means for operating said frog-point, substantially as described and shown.

2. The combination of the movable frog A, the main and siding rails E E and D D, the 15 portion C, located between the ends of the rails D D, the bed-plate B, and any suitable means for operating said frog-point, substantially as described, and for the purpose set forth.

3. The combination of the bed-plate B, the frog-point A, operating upon said bed-plate, the piece C, located between the ends of the rails D D, the rails D D and E E, the lever or arm I, attached to the frog-point A, the lever J, pivoted on the plate K, the rod H, secured 20 to the lever L, the lever L, the plate K, the sheaves G, secured to the cross-ties, and the arm of switch-stand, substantially as described, and for the purpose set forth.

In testimony whereof we affix our signatures 25 in presence of two witnesses.

HARVEY C. BRICE.
WILLIAM C. SMITH.
